UNITED STATES PATENT OFFICE.

CHARLES E. PENDLETON, OF ENID, OKLAHOMA.

ENGINE-EXHAUST COOKER.

1,411,405;

Specification of Letters Patent. Patented Apr. 4, 1922.

Application filed January 15, 1921. Serial No. 437,500.

To all whom it may concern:

Be it known that I, CHARLES E. PENDLETON, a citizen of the United States, residing at Enid, in the county of Garfield and State 5 of Oklahoma, have invented certain new and useful Improvements in Engine - Exhaust Cookers, of which the following is a specification, reference being had to the accompanying drawings.

10 This invention relates to cooking devices and particularly to a device which uses the heat of the exhaust of an engine in the cooking operation.

An object of the invention is to provide 15 a device of this character capable of being readily connected to the exhaust of an engine, and wherein the exhaust from the engine passes through the device to cook articles of food deposited therein.

20 Another object of the invention is to provide a device of this character particularly adapted for use in connection with automobiles whereby the exhaust of the engine is utilized for cooking purposes.

25 A still further object of the invention is to provide a device of this character including a housing adapted to receive a cooking chamber which cooperates with the housing to provide a heat receiving chamber and 30 wherein means are provided for causing a circulation of the exhaust from the engine within the housing to utilize the heat of the exhaust for cooking articles of food deposited within the cooking chamber.

35 With the above and other objects in view, the invention consists in the improved construction and arrangement of parts to be hereinafter more particularly described, fully claimed and illustrated in the accompanying drawings, in which:—

Figure 1 is a fragmentary side elevation of an automobile body showing the invention applied,

40 Figure 2 is an elevation and sectional view of the cooker,

Figure 3 is a side elevation of the valve operating mechanism,

Figure 4 is a plan view of the cover used for heating purposes, and

45 Figure 5 is a sectional view through the housing, showing the cooking utensils applied.

Referring to the drawings, A designates the body of an automobile including a floor 50 B and running board C. Disposed upon the floor B or the running board C is a housing

5 which may be of any desired form. The housing is secured to the running board or floor by any suitable means and is adapted to receive the exhaust from the engine. 60

A cooking receptacle or chamber 6 is provided, said chamber being smaller in diameter than the housing, the upper edges of the walls of the chamber being extended at right angles and outwardly of the chamber into 65 engagement with the upper edges of the walls of the housing 5 and serve as supporting means for the cooking receptacle 6. It will be noted that the cooking receptacle 6 is disposed in spaced relation to the inner 70 surface of the walls of the housing 5, while the bottom of the receptacle is also disposed in spaced relation to the bottom of the housing. By this arrangement, a compartment or chamber 8 is formed, which is adapted to 75 receive the exhaust from the engine and as the cooking receptacle 6 is disposed in spaced relation at all points with respect to the housing 5 except the upper edges thereof, all portions of the receptacle 6 will be subjected to the heat of the exhaust. In addition to this the housing 5 not only cooperates to provide an insulated heat chamber 8 but also serves as insulating means to prevent the contact of the atmosphere with the sides of 80 the casing 6 so that the device may be used while the automobile is in motion without danger of decreasing the temperature of the cooking chamber 6. 85

Disposed between the bottom of the chamber 6 and the housing 5, adjacent the side wall of the housing a baffle plate 9 which extends transversely of the housing, said baffle plate including a concaved portion 10 which serves to deflect the exhaust. Extending into 90 the casing and terminating beneath the concaved portion 10 of the baffle plate is an inlet pipe 11 while extending into the housing and communicating therewith on the opposite side of the baffle plate 9 is an outlet pipe 100 12. The baffle plate 9 separates the two pipes 11 and 12 so that the exhaust discharged by the inlet pipe 11 is directed by the baffle plate beneath the cooking receptacle and is caused to ascend between the walls of the cooking receptacle and the housing, the exhaust circulating therearound and then passing out through the outlet pipe 12. The inlet pipe 11 is extended beneath the floor B or running board C of the automobile to the main exhaust conduit D. The conduit D is provided with an outlet mem- 110

2
ber 13 which does not interfere in any manner with the usual passage of the exhaust from the engine into the muffler. This outlet member includes an extension 14 adapted to receive the end 15 of the inlet pipe 11. Mounted within the extension 14 is an oscillating valve 16 having a stem 17 which projects through the extension and has its end portion 18 extended at right angles exteriorly of the extension.

In order to control the quantity of exhaust discharged by the inlet pipe 11 to the housing 5, a controlling mechanism is provided, and consists of a lever 19 having its end 20 formed into a handle including a knob 21. The intermediate portion of the lever 19 is extended at right angles to the handle portion 20, while the extremity 22 of the lever is extended at right angles to the intermediate portion and in the opposite direction outwardly of the handle portion 20. Pivotally connected to the extremity 22, is a link 23 which is skewed at its intermediate portion and has its end 24 pivotally connected to the end portion 18 of the stem 17. A collar 25 is formed on the handle portion 20 in order to space the handle from the floor of the car while a collar 26 is disposed beneath the floor of the car to properly position the lever 19. By this arrangement when the lever 21 is operated, the lever 23 causes the valve 16 to open or close the extension 14 to the extent desired so that the entire quantity of heat discharged by the engine may enter the outlet pipe 12 and the housing 5 before reaching the muffler. When the exhaust is not desired, the handle 20 may be operated to close the extension so that the device does not at any time obstruct the passage of the exhaust from the engine.

A cover 25 is provided, said cover having a depending flange 26 adapted to engage the exterior surface of the upper portion of the housing 5. The intermediate portion of the inner surface of the cover is provided with an extension 27 which serves as a cap, the outer surface of the extension being adapted to engage the inner surface of the walls of the cooking receptacle 6 so as to provide a suitable cover. In this way, the single cover serves two purposes, namely, to assist in holding the receptacle 6 in position and to close the same. It is of course obvious that the cover extends over the right angular portions of the receptacle 6 so that additional insulation is thereby provided for the heat within the compartment 8. In cold weather, when the device is not being used for cooking purposes the cover may be removed, and a cover 28 substituted. This cover has a plurality of ribs projecting from the upper surface thereof, the ribs 29 radiating from the center of the cover while the ribs 30 are disposed in annular spaced relation to each other from the center of the

cover to the periphery thereof. By this arrangement, the ribs draw the heat from the housing so that the device serves the purpose of a radiator to heat the automobile.

An important feature of this device is that all portions of the receptacle 6 are exposed to the heat of the exhaust so that an even temperature is maintained which permits proper cooking of the food. A plurality of cooking utensils 31 may be disposed within the receptacle 6 to hold various articles of food to be cooked simultaneously. In addition to this the particular position of the baffle plate 9 permits circulation of the exhaust within the housing as the exhaust is discharged directly beneath one end portion of the bottom of the cooking receptacle and then rises between the walls of the receptacle 6 and the housing 5 and out through the outlet 12.

85
From the foregoing it will be readily seen that this invention provides a device capable of being applied to the floor or running board of an automobile, and in any part of the automobile. It may also be applied to the exhaust of any engine and not only permits the food to be properly cooked in view of the even distribution of heat, but renders the cooking inexpensive as no fuel is necessary and as the device is simple and compact, it occupies a small space.

90
95
What is claimed is:—

1. A cooker attachment for motor vehicles comprising a casing, heat inlet and outlet means communicating with the casing, a receptacle, the upper edge of said receptacle including a relatively broad flange, said flange extending at right angles to the outer face of the receptacle, the outer edge of said flange being adapted to engage the edge of the casing whereby the receptacle is detachably suspended within the casing in spaced relation to the walls of the casing, said receptacle being adapted to receive cooking utensils, and an unattached cover for the casing and the receptacle, said cover having a depending flange adapted to engage the exterior face of the casing, the central portion of the lower face of the cover being enlarged to provide a central projection, depending from the cover and extending inwardly of the receptacle and arranged to prevent unnecessary movement of the utensils within the receptacle, said cover also extending over and engaging the upper face of the flange and edge of the receptacle, the flange of the cover serving to hold the receptacle in engagement with the casing.

130
2. A cooker attachment for motor vehicles comprising a casing, heat inlet and outlet means communicating with the casing, a receptacle, the upper edge of said receptacle including a relatively broad flange, said flange extending at right angles to the outer face of the receptacle, the outer edge of said

flange being adapted to engage the edge of the casing whereby the receptacle is detachably suspended within the casing in spaced relation to the walls of the casing, and an 5 unattached cover for the casing and the receptacle, said cover having a flange adapted to engage the exterior surface of the casing, and an enlarged central protuberance depending from the inner face of the cover, 10 said central protuberance cooperating with

the flange of the cover to substantially provide a channel for the reception of the flange of the receptacle and the edge of the casing, to position said receptacle centrally of the casing and prevent accidental disengagement 15 of the cover.

In testimony whereof I hereunto affix my signature.

CHARLES E. PENDLETON
